(57) **CLAIM**

I claim the ornamental design for an animal toy, substantially as shown and described.

DESCRIPTION

FIG. 1 is a top, perspective view of the animal toy showing my new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top view thereof;

FIG. 7 is a bottom view thereof;

FIG. 8 is an enlarged perspective view of the clasp of the animal toy thereof;

FIG. 9 is an enlarged perspective view of the strap of the animal toy thereof; and,

FIG. 10 is another enlarged perspective view of the strap of the animal toy thereof.

A description of the appearance of the article is as follows: An animal toy. The broken lines in the drawings illustrate portions of the animal toy that form no part of the claimed design. Additionally, the diagonal lines shown in FIGS. 4, 6 and 10 represent contrasting material to the adjacent surface.
